CLAIM

The ornamental design for a garden hose attached washing tool, as shown and described.

DESCRIPTION

FIG. 1 is a perspective view of a garden hose attached washing tool, showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines showing a toy truck and garden hose in FIG. 1 depict environmental matter and form no part of the claimed design. The remaining broken lines represent portions of the garden hose attached washing tool that form no part of the claimed design.

1 Claim, 5 Drawing Sheets
